DESIGN FOR A FISHING POLE TIP

Joseph Cariddi, Brooklyn, N. Y.

Application June 6, 1945, Serial No. 119,938

Term of patent 3½ years

(CL. D31—4)

To all whom it may concern:

Be it known that I, Joseph Cariddi, a citizen of the United States, residing at Brooklyn, in the county of Kings, in the State of New York, have invented a new, original, and ornamental Design for a Fishing Pole Tip, of which the following is a specification, reference being had to the accompanying drawing, forming a part hereof.

Fig. 1 is a plan view of a fishing pole tip, showing my design; Fig. 2 is a side elevational view of the same, and Fig. 3 is a bottom plan view of the same.

I claim:

The ornamental design for a fishing pole tip, as shown.

JOSEPH CARIDDI.
